WARE

RADIO RECEIVING APPARATUS

Application filed April 20, 1925. Serial No. 24,399.

This invention relates to radio-receiving apparatus, and more particularly to apparatus of this kind in which means are provided for tuning the receiving set and in which amplifying means are provided, and in which there is some tendency toward the local setting up of sustained oscillation, which, of course, may interfere with the proper operation of the apparatus, inasmuch as such action has a tendency to interfere with the incoming signal, or even to entirely blanket the incoming signal, so as to speak, and thereby prevent the proper operation of the apparatus.

Generally stated, therefore, the object of the invention is to provide a novel and improved circuit arrangement and tuning means which can be adjusted in a manner to more or less change the capacity employed to prevent the said undesirable self-oscillation of the receiving set, thereby to obtain certain beneficial results, as will hereinafter more fully appear.

It is also an object to provide certain details and features of construction, and combinations tending to increase the general efficiency and the desirability of a radio-frequency amplifying arrangement of this particular character.

To the foregoing and other useful ends, the invention consists in the matters hereinafter set forth and claimed, and shown in the accompanying drawings, in which,—

Fig. 1 is a diagram of a radio-receiving apparatus embodying the principles of the invention.

Fig. 2 is a simplified diagram, using the ordinary Wheatstone bridge arrangement, showing the theory and the mode of operation of the invention.

Fig. 3 is a bottom view of two of the adjustable condensers shown at the left in Fig. 1.

Fig. 4 is an axial section on line 4—4 in Fig. 3.

Fig. 5 is a transverse section on line 5—5 in Fig. 3.

As thus illustrated, the hook-up or circuit arrangement shown in Fig. 1 is in a general way an ordinary one, involving a

three-stage vacuum tube amplifier. The aerial 1 may be of any suitable character and is grounded through the primary 2 of the transformer or repeating coil, as shown. The secondary coil 3 has one terminal connected to the grid 4 of the first vacuum tube, and has the other terminal connected to the stopping condenser 5 of any suitable character. The other terminal of the condenser 5 is connected to the plate 6 of the vacuum tube, and the filament 7 of the tube has its terminal connected to the batteries shown at the right of the diagram, in the ordinary manner. The second stage of amplification is of similar character, it will be seen, and a description of the circuit arrangement of one lamp or vacuum tube will be sufficient.

For tuning purposes, two adjustable condensers 8 and 9 are connected in series between the terminals of the secondary coil 3, so that the capacity and inductance are in parallel, as shown. In addition, a tap 10 is taken from one terminal of the filament 7 and carried over to the middle point 11 of the capacity shunt thus formed in parallel with the secondary coil 3 of the transformer or repeating coil. The primary coil 12 of the next transformer or repeating coil, of the second stage of amplification, is connected in circuit as shown, so that the coil 3 is in the input circuit of the lamp or vacuum tube, while the coil 12 is in the output circuit of said lamp or tube.

With this arrangement there is a tendency toward oscillation, as previously stated, owing to a sort of feed back from the plate 6 to the grid 4, during the reception of the radio-frequency signal, but with the arrangement shown, involving the use of capacities 5 and 8 and 9, and the capacity between the grid 4 and the plate 6, the harmful and undesirable oscillation is prevented. As shown by the Wheatstone bridge arrangement in Fig. 2, there is capacity in each arm of the bridge, so that all four arms of the bridge contain capacity in the proper ratio to prevent the said feed back of energy from the plate to the grid of the lamp or vacuum tube. With such arrangement, it

is found that an electrical disturbance or voltage across the points 13 and 14 will have no effect upon the points 15 and 16 or input terminals. In other words, the Wheatstone bridge arrangement is balanced, so to speak, and the points 15 and 16 remain at the same potential, so far as any electrical disturbance across 13 and 14 is concerned. In this Wheatstone bridge arrangement, as shown, there is employed as one capacity for one arm or side of the bridge the grid-to-plate capacity 4 and 6, and the other three arms of the Wheatstone bridge have the condensers 5, 8 and 9 located therein, as shown and described. The capacity 8 and 9 is employed for tuning the input circuit of the lamp or vacuum tube, as these condensers are adjustable. The condensers 8 and 9 can be separately adjustable, or they can be mounted on the same shaft, or geared together, whereby the motion of one is governed by that of the other, so that the two condensers may be varied together by a single control, but preferably in such a way as to at least approximately maintain a constant capacity ratio.

One advantage of the invention, therefore, is that its operation is independent of the voltage distribution along the coil 3,—that is to say, since the filament of the amplifier tube is connected to the physical center of the input capacity, as shown, it is therefore connected to the electrical center of the input circuit, and hence with this arrangement there is no danger that the variation in voltage distribution along the coil may upset the balance of the Wheatstone bridge arrangement thus involved in the hook-up or circuit arrangement shown and described, which is illustrative of one form of the invention.

As a further advantage, it has been found that when two capacities are connected in series, the resultant capacity variation is so greatly increased over that usually obtainable that the size of the inductance 3 may be greatly increased, and the size of 8 and 9 correspondingly reduced, and still cover the wave length range over which the circuit is ordinarily tunable. One advantage of this is that the voltage applied to the grid of the vacuum tube amplifier is much greater than is obtained by the ordinary arrangement, thus insuring greatly increased amplification for each stage.

It will be understood, of course, that in practice the different repeating coils or transformers will be so arranged, relatively to each other, that they will not affect each other, inductively, thereby to insure against interference between them. Furthermore, it will also be observed that with the circuit arrangement shown and described the grid of each lamp or vacuum tube has no physical connection to the filament of the lamp or tube, and hence has no physical connection

to any source of direct current, and hence there is no possibility of any such source impressing its voltage on the grid. With this circuit arrangement it is found that the tone quality is also improved, over that obtained with the ordinary circuit arrangement, as the tone appears to be clearer and better, which means better and more accurate reproduction.

Now, with a circuit arrangement of the character shown and described, involving the use of transformers between the first and second tubes, and between the second and third tubes, as shown, there is some difference, of course, in the action of the transformers, when high frequencies or short wave lengths are used, from what happens when low frequencies or long wave lengths are employed. In other words, the repeating coils or transformers between the tubes work better with the high frequencies than they do with the low frequencies, and the amplification is better with the high frequencies than with the low frequencies, as is well known. Therefore, in order to compensate for the decreased efficiency of the repeating coils or transformers, when low frequencies or long wave lengths are used, the invention contemplates the use of adjustable capacity, in the bridge containing the condensers 8 and 9, for the different adjustments necessary for relatively long wave lengths, thereby to cause a slight feed back in the circuits, to the grids of the tubes, thus causing the amplifying circuits to work better than would be the case if the capacity in said bridge were exactly the same for long wave lengths, as well as for short wave lengths. The longer the wave length, therefore, the greater will be the unbalancing effect as between the condensers 8 and 9,—that is to say, for the short wave lengths these two condensers will have an adjustment which results in a certain condition of the capacity in this bridge, but for longer wave lengths the two condensers will be somewhat unbalanced, and for still greater wave lengths the two condensers will be still more unbalanced, in order to bring about the desired feed back and increased action of the vacuum tubes for the longer wave lengths.

For the unbalancing of the bridge in the manner explained, and suitable arrangement can be employed. As a matter of further and special improvement, however, the condenser mechanism shown in Figs. 3, 4 and 5 can be employed for this purpose. As shown, the two condensers 8 and 9 have their movable plates mounted on a single shaft 17, the stationary plates being suitably mounted on the frame 18 of the condenser mechanism. With this arrangement, the two condensers are simultaneously adjustable, in the well known manner, to tune

the apparatus for different wave lengths. In order to unbalance the bridge, however, as between the two condensers, one movable plate 19 of the condenser 8 is cut away to form an edge 20, which is curved in the manner shown, so that when the shaft 17 is rotated in the direction of the arrow shown in Fig. 5, for the shortest wave lengths, the movable plates will all be above the stationary plates; but when the rotation is continued, in order to bring the movable plates partially between the stationary plates, the end or corner portion 21 of the said cut-away movable plate will descend a distance before the curve 20 begins to subtract from this plate, so that the subtraction is progressive, so to speak, and whereby the unbalanced effect as between the two condensers is also progressive and reaches its maximum when the movable plates are entirely between the stationary plates; for at such time there is subtracted from one of the movable plates the area included between the curve 20 and the curve 22, which latter represents the curved edges of all the movable plates, as well as the curved edges of the stationary plates. When the movable plates are all above the stationary plates for the shortest wave lengths, if there be some difference between the capacity of the two condensers, because of the fact that the mutilated plate 23 having the edge 20 has its straight upper edge 24 removed for the distance between the points 25 and 26, it is compensated for by adjustment of the condenser 5 to insure the exactly balanced condition of the bridge desirable for the short wave lengths or high frequencies.

Of course, the invention contemplates the adjustment of the capacity of the bridge containing the condensers 8 and 9, for the longer wave lengths, and while the mechanism shown for doing this is convenient and efficient and desirable in different ways, it is obvious that any suitable means can be employed for insuring the balanced condition of the capacity for the short wave lengths, and for insuring the desired degree of adjustment of the capacity for the longer wave lengths.

While the condenser 8 is shown with only one plate cut away to reduce the area thereof, it will be understood that the difference in area between the two condensers and the difference in capacity can be accomplished in any suitable or desired manner. Thus a differential condenser is provided, the condenser being made in two sections, so to speak, and the differential between the two condensers being variable, and being greater for the longest wave lengths than for shorter wave lengths, in the manner explained. Of course, as shown and described, it is one of the movable plates of the condenser which is cut away to reduce its area, but it will

be understood that any plate or plates of the condenser can be reduced in area, to obtain the desired variable differential between the two simultaneously adjustable condensers, if such is necessary or desirable.

Now it will be understood that the normal operation or functioning of the Wheatstone bridge arrangement, as illustrated in Fig. 2, requires that this Wheatstone bridge be balanced, which means that the ratio of 8 to 9 must be the same as the ratio of 4, 6 to 5, or that the ratio of 8 to 4, 6 must be the same as the ratio of 9 to 5, in order to obtain the balanced characteristic of the Wheatstone bridge arrangement. Then, as explained, in order to obtain the desired feed back, to improve the receiving action of the radio set when receiving long wave lengths, this balance of the Wheatstone bridge is more or less disturbed, as by the simultaneous adjustment of the two condensers 8 and 9, giving the aforesaid differential, or by disturbing the adjustment of the condenser 5, thereby to unbalance the Wheatstone bridge and bring about the desired feed back to improve the action of the amplifying means. Of course, any one or all of the vacuum tubes or lamps shown and described, except the last, can be made subject to this feed back, and, of course, in order to prevent any of the feed back from reaching the aerial, the unbalanced Wheatstone bridge effect can be confined to the second vacuum tube or stage of amplification and to any subsequent stages of amplification, instead of being applied to the first stage of amplification shown at the left of Fig. 1 of the drawings. But, in any event, the invention contemplates a Wheatstone bridge arrangement the normal balance of which can be disturbed, more or less, to provide a feed back which will improve the receiving action in the manner explained, when the longer wave lengths are employed.

The Wheatstone bridge arrangement, of course, may be employed for any suitable or desired purpose. As shown, it is employed to counteract the tendency toward self-oscillation, as explained, but it can be used for any suitable or desired purpose, together with the means for disturbing or unbalancing the Wheatstone bridge, without departing from the spirit of the invention.

Of course, the simple bridge in which the condensers 8 and 9 are located, as well as the simple bridge containing the condensers 17 and 18, is merely a transverse bridge between the two parallel conductors 19 and 20, and between the two parallel conductors 21 and 22, and are different from the so-called Wheatstone bridge arrangement involved in the apparatus, which Wheatstone bridge arrangement is shown diagrammatically in Fig. 2 of the drawings. Of course, so far as the provision of self-oscillation is

concerned, the condensers 8 and 9 may have the same capacity, and in such case the condenser 5 will be adjusted to equal the capacity of 4 and 6, whereby the ratio between 8 and 9 will be the same as the ratio between 4, 6 and 5 and the ratio between 8 and 4, 6 will be the same as the ratio between 9 and 5, for the reasons explained. However, in order to provide a slight regenerating effect, or feedback, as explained, one of the adjustable condensers can be given a slightly different capacity, such as the condenser 8 has by reason of its abbreviated plate 23, as previously explained.

It will be seen that the unbalancing of the Wheatstone bridge arrangement, by the simultaneous adjustment of the condensers 8 and 9, is automatic, so to speak, inasmuch as this unbalancing is incidental to the tuning 20 of the apparatus by adjustment of these condensers. The condenser 5 can be set in such fixed adjustment thereof as will serve the purpose for all adjustments of the condensers 8 and 9, so that in tuning the apparatus for different wave lengths, it is only necessary to adjust the condensers 8 and 9, as by this adjustment alone the progressive unbalancing of the Wheatstone bridge is accomplished in the manner explained. In 25 other words, the unbalancing of the bridge is unavoidable, and is an unavoidable incident to the tuning of the apparatus by adjustment of the condensers 8 and 9, and the unbalancing is not accomplished by any separate and deliberate or special act on the 30 part of the user. In this way the degree of unbalance for each wave length is predetermined, so to speak, by the fixed, relative formation of the two condensers 8 and 9, as they are on the same shaft and their structural relation to each other cannot be changed. Hence, when the apparatus is manufactured, the condenser 5 can be adjusted and set as desired, and the user will 35 then simply simultaneously adjust the two condensers 8 and 9, and in this way the apparatus is originally assembled and made in a manner to insure the unbalancing desired, when the condensers 8 and 9 are adjusted in one direction, and the progressive return of the bridge to a condition of more balance 40 when these condensers are adjusted in the opposite direction.

Without disclaiming anything, and without prejudice to any novelty disclosed, what I claim as my invention is:

1. A radio receiving apparatus comprising a vacuum tube or lamp having a filament and a grid and a plate and elements forming in effect a Wheatstone bridge arrangement, with capacity in each arm of the bridge, one such capacity being formed by the grid-to-plate capacity of said lamp or tube, having a secondary of an inductive 60 coupling from an aerial to an input circuit

of the lamp connected between opposite points on said bridge, having an output circuit of the lamp connected between the other two opposite points on said bridge, and having tuning instrumentalities relatively formed and adapted for automatically and unavoidably causing an unbalancing of said bridge to a predetermined extent suitable for the lower frequencies or longer wave lengths, in the tuning operation, thereby to produce some feed back and a consequent better action of the vacuum tube for the longer wave lengths.

2. A radio receiving apparatus comprising a vacuum tube or lamp having a filament and a grid and a plate and elements forming in effect a Wheatstone bridge arrangement, with capacity in each arm of the bridge, one such capacity being formed by the grid-to-plate capacity of said lamp or tube, having instrumentalities for unbalancing said bridge for the lower frequencies or longer wave lengths, thereby to produce some feed back and a consequent better action of the vacuum tube for the longer wave lengths, said instrumentalities comprising two condensers mounted on the same shaft, one condenser forming the capacity of one arm and the other condenser forming the capacity of another arm of said Wheatstone bridge arrangement, with one of the movable plates of one condenser of less area than the others and formed to progressively unbalance the two condensers as the shaft is turned in a direction to tune the apparatus for the longer wave lengths.

3. A radio receiving apparatus comprising a vacuum tube or lamp having a filament and a grid and a plate and elements forming in effect a Wheatstone bridge arrangement, with capacity in each arm of the bridge, one such capacity being formed by the grid-to-plate capacity of said lamp or tube, having instrumentalities for unbalancing said bridge for the lower frequencies or longer wave lengths, thereby to produce some feed back and a consequent better action of the vacuum tube for the longer wave lengths, said instrumentalities comprising a pair of adjustable condensers each forming the capacity of one arm of the Wheatstone bridge arrangement and relatively formed to cause one condenser to have more capacity than the other, when both are adjusted for the longer wave lengths, but having substantially the same capacity when both are adjusted for the shortest wave lengths.

4. A radio receiving apparatus comprising a vacuum tube or lamp having a filament and a grid and a plate and elements forming in effect a Wheatstone bridge arrangement, with capacity in each arm of the bridge, one such capacity being formed by the grid-to-plate capacity of said lamp or tube, having instrumentalities for unbalancing said bridge

for the lower frequencies or longer wave lengths, thereby to produce some feed back and a consequent better action of the vacuum tube for the longer wave lengths, said instrumentalities comprising two condensers mounted on the same shaft, one condenser forming the capacity of one arm and the other condenser forming the capacity of another arm of said Wheatstone bridge arrangement, with one of the movable plates of one condenser of less area than the others and formed to progressively unbalance the two condensers as the shaft is turned in a direction to tune the apparatus for the longer wave lengths.

5. The combination of a plurality of condensers on the same shaft for tuning the same circuit, having a tube connected to the electrical circuit connection between the two 10 condensers, the condensers being connected in series, and the condensers being so relatively formed that the ratio between the condensers is variable automatically by the adjustment thereof in unison.

25. 6. In radio apparatus, the combination of instrumentalities forming in effect a Wheatstone bridge arrangement having condensers in two of the arms thereof, the two condensers being connected together for simultaneous adjustment only, and a capacity in another arm of said Wheatstone bridge arrangement, said condensers being relatively formed to co-operate with said capacity to progressively unbalance the bridge by the 30 simultaneous adjustment of said condensers in one direction, and to progressively restore the bridge to a more balanced condition by adjustment in the opposite direction.

7. A structure as specified in claim 6, in 40 combination with other elements forming with said Wheatstone bridge arrangement a radio circuit which can be tuned for different wave lengths by the said simultaneous adjustment of said condensers, whereby 45 there will be a greater unbalance of the bridge for some wave lengths than for others.

8. A structure as specified in claim 6, in combination with elements forming with said Wheatstone bridge arrangement a radio receiving apparatus which can be tuned for different wave lengths by the said simultaneous adjustment of said condensers, and said capacity being an adjustable condenser which can be set at a desired fixed adjustment for all adjustments of said two condensers.

9. A structure as specified in claim 6, said capacity being an adjustable condenser which can be set at a desired fixed adjustment for all adjustments of said two condensers.

Specification signed this 10th day of April, 1925.

BYRON B. MINNIUM.
